UNITED STATES PATENT OFFICE.

DANIEL J. DUNBAR, OF PHILADELPHIA, PENNSYLVANIA.

RETAINING MEANS FOR WINDOW-SASHES.

1,270,387.

Specification of Letters Patent. Patented June 25, 1918.

Application filed August 10, 1917. Serial No. 185,413.

To all whom it may concern:

Be it known that I, DANIEL J. DUNBAR, a citizen of the United States, residing at Philadelphia, in the county of Philadelphia and State of Pennsylvania, have invented 5 certain new and useful Improvements in Retaining Means for Window-Sashes, of which the following is a specification.

My invention consists of improved retaining means for window sashes. One object 10 of my invention is to provide retaining means of the above mentioned character which will efficiently hold slideable window sashes in any desired position without the requirement of the customary ropes, cords, and 15 counterbalancing means.

Another object is to make my invention of simple construction, durable, and so that it can be easily and quickly manufactured 20 and applied to windows.

These objects, and other advantageous ends which will be described hereinafter, I attain in the following manner, reference being had to the accompanying drawings in 25 which

Figure 1 is a front elevation of a window constructed in accordance with my invention.

Fig. 2 is an enlarged section on the line 30 2-2 of Fig. 1.

Fig. 3 is a fragmentary sectional elevation taken on the line 3-3 of Fig. 2.

Fig. 4 is a fragmentary outside elevation on a smaller scale than Fig. 3 showing the 35 side of the window frame with the sashes removed.

Fig. 5 is a transverse section through a spring holder which forms a part of my invention.

Fig. 6 is a view of similar nature to Fig. 40 4 showing one of the cover plates removed in order to illustrate a modification in which the retaining springs each includes two leaves or strips.

Referring to Figs. 1 to 5 inclusive of the drawing, 1 represents the frame of a window having upper and lower slideable sashes 2 and 3 respectively. Each side 4 and 5 of the frame 1 has a cavity 6 formed therein, 45 and since each of these cavities is designed to house similar elements, it will only be necessary to describe the elements contained within and adjacent one of the cavities 6, and it will be understood that the other of

said cavities 6 contain similar elements 55 which perform the same function as those specifically described.

Considering the side 4 of the frame 1, its cavity 6 contains two rollers or wheels 7 and 8 mounted one above the other as clearly 60 shown in Fig. 3.

The frame 1 has grooves 9 and 10 which are arranged parallel and vertically. These grooves communicate with the cavity 6 as clearly illustrated, and the rollers 7 and 8 65 preferably have their axes in different vertical planes, so that the roller 7 has a portion included in a plane passing through the groove 9, and the roller 8 has a portion included in a plane passing through the 70 groove 10.

The sash 2 has a thin strip 11 of leather, rubber, metal, or other flexible material, this strip being retained by a corner piece 12 on said sash, the corner piece being detachably secured by means of screws 13 75 which are inserted at different points throughout the height of the sash.

A portion of the strip 11 projects into the groove 10 and is designed to slide through 80 the cavity 6. A bowed spring 14 has one of its ends passing through a slot 15 in a sleeve 16, there being a block of wood 17 within said sleeve and through which the spring 14 extends. A screw 18 serves to 85 bind the spring 14 laterally within the block 17 and also serves to hold the block and sleeve to the frame (see Figs. 3 and 5). The opposite end of the spring 14 is free and is designed to press the strip 11 against the 90 roller 8 as said strip passes through the cavity 6, thus creating a friction which is sufficiently intense to retain the sash 2 in any position into which it is manually moved.

The spring 14 is backed by a threaded adjusting screw 19 which fits within a tapped bushing 20 mounted in the frame as clearly shown in Figs. 2 and 3. The adjusting screw 19, in the present instance, passes entirely through the frame and has its head 21 95 outside of said frame, so that by turning the adjusting screw, various pressures can be brought to bear upon the spring 14 to increase or reduce the intensity of the friction upon the strip 11.

In like manner, the lower sash 3 has a 100 flexible strip 22 secured thereto by a corner piece 23 through which pass screws 24. The

strip 22 extends within the groove 9 and is designed to slide therein and through the cavity 6.

Another retaining spring 25, which is mounted similarly to the spring 14, is designed to press the strip 22 into engagement with the peripheral edge surface of the roller 7. The intensity of the pressure of said spring 25 against the strip 22 can be varied by an adjusting screw 26 which fits within a bushing 27 in the frame 1 and has its head 28 in a position accessible from the inside of the frame.

A cover plate, made in three sections 29, 30 and 31, is designed to cover the cavity with the exception of openings 32 and 33 to permit the strips 11 and 22 to pass therethrough, this arrangement being clearly shown in Fig. 4.

20 A spacing rib 34 is secured to the frame 1 between the paths of movement of the sashes 2 and 3. Therefore, since the springs 14 and 25 are positioned at opposite sides of the rollers 7 and 8, and have a tendency to move 25 toward each other, the sashes 2 and 3 will have a tendency to be brought into frictional engagement with the rib 34. The frame 1 is also preferably provided with removable beads 35 and 36 adjacent the inside surface 30 of the lower sash 3, and the outside surface of the upper sash 2 as clearly shown in Figs. 1, 2, and 3.

It will be noted that the springs 14 and 25 serve as automatic means for applying friction to the strips which are secured to the sashes, and the rollers 7 and 8 being rotatable, permit an easy movement of the sashes when it is desired to actuate the same.

In the form of my invention shown in 40 Fig. 6, each of the strip-engaging springs 37 is made up of two leaves or strips 38 and 39 so that the tension of the spring is distributed throughout a number of leaves instead of through a single leaf as in Figs. 1 to 5 inclusive. In all other respects the elements illustrated in Fig. 6 are similar to those described in connection with Figs. 1 to 5 inclusive, and I have therefore given similar parts corresponding reference numerals.

50 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what 60 I claim as new and desire to secure by Letters Patent is:

1. The combination of a window frame having a longitudinally extending groove, a window sash, a strip projecting edgewise from the sash and secured thereto through-

70 out its length, said strip slidably fitting within said groove and bridging the parting between the side edge surface of said sash and the adjacent side surface of said frame, means for engagement with one side surface of the strip, and means automatically operative upon an opposite side surface of said strip for pressing said first side surface of the strip into engagement with said first means, substantially as described.

75 2. The combination of a window sash, a strip having a portion projecting edgewise from the sash and secured thereto within its length, said strip bridging the parting between the side edge surface of said sash and the adjacent side surface of said frame, a rotatably mounted roller having its axis substantially parallel to the plane of movement of said sash, and automatically operative means for pressing the projecting portion of the strip into engagement with the peripheral surface of said roller, substantially as described.

80 3. The combination of a window frame having a groove formed therein and a cavity with which the groove communicates, a roller mounted in said cavity, a sash, a strip projecting edgewise from the sash and secured thereto within its length, said roller having its axis substantially parallel to the plane of movement of said sash, the projecting portion of said strip being adapted 85 to slide within said groove and through said cavity and bridging the parting between the side edge surface of said sash and the adjacent side surface of said frame, and means for pressing the projecting portion of said strip into engagement with said roller, substantially as described.

90 4. The combination of a window frame having a groove formed therein and a cavity with which the groove communicates, a roller mounted in said cavity, a sash having a strip projecting therefrom and secured thereto within its length, said strip being designed to slide within said groove and through said cavity, and a spring adapted 100 to press a side surface of said strip into engagement with said roller, substantially as described.

105 5. The combination of a window frame having a groove formed therein and a cavity with which the groove communicates, a roller mounted in said cavity, a sash having a strip projecting therefrom and secured thereto within its length, said strip being designed to slidably fit within said groove and to pass 110 through said cavity, a spring adapted to press said strip into engagement with said roller, and adjusting means for varying the intensity of pressure of said spring on the strip, substantially as described.

115 6. The combination of a window frame having a groove formed therein and a cavity with which the groove communicates, a roller 120

mounted in said cavity, a sash having a strip projecting therefrom and designed to slidably fit within said groove and through said cavity, a spring adapted to press said strip into engagement with said roller, said roller and spring being mounted within said cavity, and an adjusting screw extending through said frame and adapted to vary the intensity of pressure of said spring 10 against the strip, substantially as described.

7. The combination of a window frame having a groove formed therein and a cavity with which the groove communicates, a roller mounted in said cavity, a sash having 15 a strip projecting therefrom and designed to slidably fit within said groove and through said cavity, a spring adapted to press said strip into engagement with said roller, said roller and spring being mounted 20 within said cavity, a threaded bushing within said frame, an adjusting screw mounted in said bushing and having a portion adapted to engage said spring to vary the intensity of pressure of the latter against said 25 strip, substantially as described.

8. The combination of a window frame having two grooves therein spaced apart and a cavity with which the grooves communicate, two rollers within said cavity and having their axes between planes passing longitudinally through said grooves, two sashes, each sash having a strip projecting therefrom and adapted to slide within a respective groove and through the cavity, and 35 means for pressing said strips into engage-

ment with the respective rollers, substantially as described.

9. The combination of a window frame having two grooves therein spaced apart and a cavity with which the grooves communicate, two rollers within said cavity and having their axes between planes passing longitudinally through said grooves, two sashes, each sash having a strip projecting therefrom and adapted to slide within a respective groove and through the cavity, and means for pressing said strips into engagement with the respective rollers, said rollers having their axes in different vertical planes, substantially as described. 40 45 50

10. The combination of a window frame having a groove formed therein and a cavity with which the groove communicates, a strip projecting from said frame, means for engagement with said strip, a sleeve having a slot, a block mounted within the sleeve, a spring having one end extending through said slot and into the block and adapted at its other end to engage and press said strip against said means, and a screw extending through said block and adapted to laterally engage the spring, substantially as described. 55 60

In testimony whereof I have signed my name to this specification in the presence of two subscribing witnesses.

DANIEL J. DUNBAR.
